Int. Cl. D29—02; D20—03
U.S. Cl. D10—109

FIG. 2

FIG. 1

FIG. 4

FIG. 1 is an elevational view of the changeable distress flag showing my new design, the changeable insert being folded and inserted into the pocket on the flag;

FIGS. 2 and 3 are enlarged perspective views of opposite sides of the changeable insert partly unfolded; and

FIG. 4 is an elevational view of the distress flag, the changeable insert being omitted for illustrative purposes.

The flag and changeable insert are shaded to indicate contrast.

The indicia is shown in broken lines on the insert for illustrative purposes only.

The rear of the flag is flat and unornamented.

I claim:

The ornamental design for a changeable distress flag, as shown.
